UNITED STATES PATENT OFFICE.

JOHN LAWRENCE NICHOLSON, OF JERSEY CITY, NEW JERSEY.

ADJUSTABLE SKIRT-HOLDER.

SPECIFICATION forming part of Letters Patent No. 729,208, dated May 26, 1903.

Application filed March 3, 1902. Serial No. 96,539. (No model.)

To all whom it may concern:

Be it known that I, JOHN LAWRENCE NICHOLSON, a citizen of the United States, and a resident of Jersey City, in the county of Hudson and State of New Jersey, (having my post-office address at No. 133 Bay View avenue, in said Jersey City,) have made certain Improvements in Ladies' Adjustable Skirt-Holders, of which the following is a specification, reference being had to the accompanying drawings, in which—

Figure 1 illustrates my attachment in use. Fig. 2 is an elevation of my improved skirt-holder. Fig. 3 is an elevation of clamp used for grip in open position to receive skirt. Fig. 4 is edge view of clamp or grip closed.

Prior to my invention there have been various devices patented (as I am informed) to lift a woman's skirt from off the ground; but women have failed to recognize any value in them, for the reason that any device which permits the weight or pull of the skirt to rest at the place of the gripping (without any give) will certainly injure the garment. Also at certain localities—say at the crossing of a street—a skirt needs to be lifted higher than at other places. This need is quickly and easily cared for by the shifting of the belt, as hereinafter stated. Also the combination peculiar to my invention does not permit the dead-weight of the skirt to rest upon the grip.

A illustrates a band or belt of such material as may be preferred—that is to say, fibrous, as shown, leather, or a metallic chain—which goes around a woman's waist, or thereto.

B is a ring fastened at one end of band A. It may be in the form shown—that is to say, circular—or in any other form or shape to answer the intent stated.

C is what I term a "grip" or "clamp," fastened by loop c or its equivalent to end a of band or belt A. Clamp C may be made in the form or shape shown or circular or otherwise, as preferred, and the mechanism remain practically the same. At the lower end of clamp C, Fig. 3, is formed spring c', so as to force arm c² and arm c³ into an open position to allow the skirt to be inserted, as shown in Fig.

1, after which arms c² and c³ are forced together and locked by hook c⁴, as shown in Fig. 4. There are many known ways other than spring c' whereby arms c² and c³ may be held to act in conjunction to grip a skirt. A pivot or equivalent may be acceptable at times. A buckle a' is sometimes employed to lengthen or shorten band A. I may not at all times employ said buckle a', as the tongue thereof, which is inserted through the band, as shown, may not be desirable. Therefore an automatic or slide catch or an equivalent may be used and attached at any place upon belt A as may be preferred.

By means of buckle a' or its equivalent band A may be lengthened to such an extent that the skirt may be let down to its normal position or raised, as may be desired, without ungrinding the skirt. Buckle a' or equivalent also provides means by which the belt 7c may be adapted to any-size person. It will be noted that by the band being loose and not firmly fastened at any one place (other than the skirt) the band A is permitted to run or play through ring B. This feature of the combination greatly preserves the skirt from being injured, in that when the skirt is being held up a sudden jerk or pull of the garment will not rend it where the grip is made, for the reason that the force of the pull will not concentrate at the place of the grip, but will be checked gradually at the waist of the wearer.

Buckle a' will not at all times be employed. Neither need the wearer resort to the buckle to raise the skirt to a higher position, as the band A may be slipped around the waist to the right or left, as preferred, which will conveniently raise the skirt to a higher position, for when the band is shifted part a of the band A will follow, drawing the skirt with it. The belt when adjusted will remain in the position placed and will tighten around the waist of its own accord and be held by the weight or pull of the skirt by the band A working through ring B.

Having described my invention, I claim—

A dress-skirt supporter, comprising a band A, having a ring B, attached thereto at one end, said band passing through the ring to

form a loop to be passed around the waist of the wearer, a buckle on the band to adjust the length of the band and form a loop for supporting a grip, and a grip held in the loop to engage a dress-skirt, substantially as described.

In testimony whereof I have signed my

name to this specification in the presence of two subscribing witnesses.

JOHN LAWRENCE NICHOLSON.
